UNITED STATES PATENT OFFICE.

SVEN G. BOLIN, OF KANSAS CITY, MISSOURI.

METAL DOOR.

1,138,837.

Specification of Letters Patent. Patented May 11, 1915.

Application filed February 6, 1913. Serial No. 746,467.

To all whom it may concern:

Be it known that I, SVEN G. BOLIN, a subject of Sweden, residing at Kansas City, in the county of Jackson and State of Missouri, have invented certain new and useful Improvements in Metal Doors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to metal doors, and more particularly to a means for securing trimmings thereto, and has for its principal object to provide a spring clip whereby various designs of beading and molding may be held, to present a pleasing appearance to the finished article.

In accomplishing this object I have provided the details of structure hereinafter described and illustrated in the accompanying drawings, wherein:

Figure I is a perspective view of the lower portion of a metal door showing a molding in position around the lower panel. Fig. II is an enlarged detail perspective view of one corner of the door and panel. Fig. III is a sectional view through one of the stiles, showing the molding spaced from the clip, parts being broken away for better illustration. Fig. IV is a similar view showing the molding in position. Fig. V is a detail perspective view of a portion of the spring clip.

Referring more in detail to the parts:— 1 designates the stiles, 2 the lower cross rail, 3 an intermediate cross rail and 4 the panel of a metal door of any ordinary construction.

Welded, or otherwise secured to the panel 4, adjacent the stiles and cross rails, is a spring clip 5 which comprises a flat portion 6 which is secured to the panel, and a spring portion 7 having an upturned edge 8 adapted to face toward the center of the panel.

The molding may be of any suitable design but comprises a flat portion 9 which is adapted to lie against the panel and has an upwardly curved spring portion 10 adapted for projection beneath the spring clip 5 to lock the molding in place.

In applying the molding to a door, corner pieces 11 are formed by mitering a portion of the molding and bending it to fit each of the corners to be filled, and placing it so that the spring portion 10 is projected beneath the spring clip 5. Straight molding sections are applied in the same manner to fill the spaces between the corner sections. It is apparent that by this method metal doors may be made up in stock sizes and moldings or other trimmings added to meet the requirements of different styles of architecture.

I do not wish to limit myself to the particular position of the spring clip, as it could be placed so as to face the stiles and cross bars without departing from the scope of the invention.

Having thus described my invention, what I claim as new therein, and desire to secure by Letters-Patent, is:

1. In a metal door, an inset panel, an inwardly facing spring clip fixed to and spaced from the edges of the panel, and a mitered and square ends and spring lips adapted for projection beneath the spring lips seated for projection beneath the spring clips on the panel, and straight members having square ends adapted for projection between and abutment with the square ends of the corner members, and having spring lips adapted for projection beneath the spring clips on the panel, whereby the corner members are locked firmly in position.

2. In a metal door, stiles and cross rails, a panel set in from said stiles and cross rails to form a shoulder, a fastening member fixed to said panel adjacent said shoulder and having a spring lip opening toward the center of said panel, a molding comprising corner members having mitered and square ends, and a spring lip adapted for projection beneath the spring lip of the fastening member, and straight sections having square ends adapted for abutment with the square ends of the corner sections and having spring lips adapted for projection beneath said fastening member to lock the corner sections in position.

In testimony whereof I affix my signature in presence of two witnesses.

SVEN G. BOLIN.
